Primary Examiner — Cynthia Ramirez

(74) Attorney, Agent, or Firm — Donald J. Ersler

(57) **CLAIM**

The ornamental design for a joystick handle, as shown and described.

DESCRIPTION

FIG. 1 is a top perspective view of a joystick handle incorporating my new design;

FIG. 2 is a bottom perspective view thereof;

FIG. 3 is a top plan view thereof;

FIG. 4 is a bottom plan view thereof;

FIG. 5 is a left side view thereof;

FIG. 6 is a right side view thereof;

FIG. 7 is a front elevation view thereof; and,

FIG. 8 is a rear elevation view thereof.

The broken lines shown in the drawings illustrate portions of the joystick handle that form no part of the claimed design.
